UNITED STATES PATENT OFFICE.

ANDREW A. KUCHER, OF CHESTER, PENNSYLVANIA, ASSIGNOR TO WESTINGHOUSE ELECTRIC & MANUFACTURING COMPANY, A CORPORATION OF PENNSYLVANIA.

REFRIGERATOR.

Application filed June 4, 1923, Serial No. 443,382. Renewed November 23, 1926.

My invention relates to refrigerating machines, particularly to small capacity machines of the compression type which are suitable for household use, and it has for an object to provide a novel method and means for maintaining a supply of lubricant for the mechanism which shall be effective during long periods of service without attention.

It has for another object to provide, in a machine which employs a working fluid having as constituents a refrigerant and a lubricant which together form a homogeneous mixture or physical solution, a method and means for separating out the refrigerant from the lubricant.

It has for a still further object to utilize the heat of the motor and of the compressor to vaporize off the refrigerant contained in the liquid working fluid and to maintain an ample supply of the remaining liquid, which is substantially lubricant, for sealing and lubricating the mechanism.

These and other objects, which will be made apparent throughout the further description of the invention may be attained by the employment of the apparatus hereinafter described and illustrated in the accompanying drawing in which Fig. 1 is a view partly in section and partly in elevation of a compression refrigerator in which my invention may be practiced; and Fig. 2 is a sectional elevation taken on the line II—II of Fig. 1.

In refrigerators of the household type, it has been proposed to enclose the compression mechanism in a fluid tight chamber to prevent the escape of the working fluid and, for this reason, some means for the lubrication thereof must be provided which will operate without attention continuously and reliably for long periods of time, as for example, for one or more years. It has heretofore been proposed to employ in compression refrigerators a lubricant which is immiscible with the refrigerant. Many liquids possessing to a greater or less extent this property, have been used, generally with incomplete success, since no combination of lubricant and refrigerant has been found in which the lubricants do not mix to some extent when brought together under the conditions of agitation obtaining in a compression refrigerator. Mechanical separators of various types have

been employed in connection with machines of this character to facilitate the segregation of the lubricant and the refrigerant. This expedient has improved the operation but has not resulted in accomplishing sufficiently complete segregation of the fluids to enable compression refrigerators utilizing a compound working fluid of this character to operate for long periods without the replacing of the lubricant.

In my machine, I employ a working fluid consisting of a refrigerant and a lubricant which readily mix one with the other to form a homogeneous or liquid solution, and which I have disclosed in my copending application, serially numbered 617,844, filed February 8, 1923 and entitled "Refrigerators". This working fluid is of such character that its constituents are not separable mechanically, but only by vaporization.

In the apparatus of the present invention, I supply a mixed refrigerant vapor and liquid working fluid to the compressor which, when discharged thereby, are impinged upon a baffle. This baffle substantially separates the vapor and the liquid, the vapor passing on to the condensing coils and the liquid working fluid falling upon the compressor. The liquid flows over the compressor and a portion of the motor casing and thereby absorbs a large quantity of the heat generated by the compressor and the motor. The heat absorbed is sufficient to vaporize off an extremely high percentage of the refrigerant held in solution in the liquid working fluid and the liquid thus treated, which is substantially lubricant, is drained to a reservoir from which it is conveyed to the working parts of the apparatus as is required.

Referring to the drawings for a detailed description of my invention, I show the condensing chamber of a refrigerator of a type disclosed in a copending application of mine, serially numbered 509,672, filed October 22, 1921, and entitled "Refrigeration machine". In this type of machine, my novel method of operation may be carried out, but it is to be understood that the invention may be practiced in other types of compression machines and that the apparatus illustrated and herein described is employed by way of example and as an aid in presenting a clear exposi-

tion of my invention. As illustrated, 10 designates a condensing chamber comprising a bell or dome 11 secured to a base plate 12 and to a pedestal 13 by bolts 14. A compressor 15 driven through a shaft 16 by a suitable motor 17 is disposed within the chamber. Supported upon the base plate 12 is an inverted cup-shaped casting 18 which forms a casing for the motor and which also

10 supports the compressor 15.

The fluid discharged by the compressor 15 is conveyed by a conduit 19 toward a baffle 21. The baffle 21 is disposed over the compressor 15 and is of such conformation as to cause liquid working fluid, which may be impinged thereon, to fall downwardly upon the compressor. Cast integral with the motor casting 18 and surrounding the upper surface thereof is a trough 22 for catching the liquid working fluid which falls upon the compressor and which flows downwardly over the motor casing. Communicating therewith and also cast integral with the motor casing is a reservoir 23 for storing the liquid working fluid which has been caught by the trough 22. The liquid working fluid is conveyed from the reservoir 23 to the compressor 11 by means of an inverted bent tube 24 having an open inlet 25 and having its discharge portion 26 arranged coaxially with the compressor.

Disposed in the upper portion of the condensing chamber 10 is a plurality of condensing coils 27 having water inlet and outlet connections which pass without the chamber. Supported upon the upper surface of the motor casing by brackets 28 is a circular deflector 29 which is so arranged as to prevent liquid, which has been condensed upon the coils 27, from entering the trough 22 while falling to the lower portion of the condensing chamber. The liquid collected in the lower portion of the condensing chamber is conveyed by means of a passage 30, arranged within the motor casing 18, and a connecting conduit 31 to an evaporator 32. The flow of liquid through the passage 30 is controlled by means of a reducing valve 33 which is actuated by a float 34. The conduit 31 terminates near the lower portion of the evaporator 32 for the discharge of the liquid working fluid.

Vapor generated in the evaporator 32 is returned to the compressor by means of a conduit 35. The lower portion of the conduit 35 is formed into a U-tube having its free open end disposed above the level of the liquid in the evaporator and having its curved portion extending well below the level of the liquid in the evaporator. A small aperture 36, located in the curved portion of the U-tube and below the normal level of the liquid, permits a small amount of liquid working fluid to enter the vapor conduit 35 and to be carried upwardly to the compressor. A con-

duit 37 communicates with the lower portion of the motor chamber and with the conduit 35 for the return to the compressor 15 of liquid working fluid which has been employed to lubricate the motor.

The operation of the apparatus thus described is as follows: The condensing chamber 10 and the evaporator 32 are filled to a level, such as indicated on the drawing, with a suitable liquid working fluid. As stated heretofore, this liquid working fluid may be composed of a lubricant and a refrigerant which together form a homogeneous mixture or physical solution. It will be noted that the level of the liquid working fluid in the condensing chamber is below the level of the trough 22. After the motor 17 has been started, the compressor 15 discharges through the conduit 19 a commingled liquid working fluid and refrigerant vapor which are impinged upon the baffle 21. The refrigerant vapor is substantially separated from the liquid working fluid and passes outwardly to the coils 27 upon which it is condensed by the cooling action thereof. The condensed refrigerant falls to the lower portion of the condensing chamber, and upon sufficient rise of liquid level therein, the float 34 will act to open the reducing valve 33 to permit a flow of liquid working fluid through the passage 30 and conduit 31 to the evaporator 32. Within the evaporator the refrigerant contained in the liquid working fluid is evaporated by the absorption of heat from the refrigerant box (not shown), and the refrigerant vapor is returned by the conduit 35 to the inlet of the compressor 15. The small aperture 36 being disposed below the level of the liquid in the evaporator, a small quantity of liquid working fluid flows into the conduit 35 and is entrained in the refrigerant vapor being conveyed to the compressor.

The liquid working fluid which has been separated from the refrigerant vapor by the baffle 21 falls downwardly upon the upper surface of the compressor 15, and forms a thin film of liquid thereon. It then flows downwardly in a film over the outer surface of the compressor and is deposited upon the hottest portion, that is the upper surface, of the motor casing 18. It flows over and down the outer surface of the motor casing 18 and is caught in the trough 22 after which it drains to the reservoir 23. In passing over the compressor 15 and the motor casing 18, a considerable portion of the heat generated by the motor 17 and the compressor 15 is absorbed, and a very high percentage of the refrigerant, which is contained in the liquid working fluid, is vaporized off and passes to the condensing coils 27 and thence to the lower portion of the condensing chamber. The liquid, therefore, which enters the reservoir 23 is substantially lubricant and this so-called lubricant is conveyed by means of the tube 24.

and the pressure prevailing within the condensing chamber to the upper end of the compressor. It may then be utilized to form a liquid seal between the rotor and the casing 5 of the compressor and to lubricate the working parts of the compression mechanism as may be required. An ample supply is always maintained within the reservoir 23, and should the flow of the liquid thereto be greater than that required, the excess will eventually flow over the edge of the trough 22 and commingle with the relatively large body of liquid working fluid in the lower portion 10 of the condensing chamber. The lubricant discharged by the conduit 24 may be conveyed through the working parts of the apparatus by any approved means, and after passing therethrough is returned to the inlet of the compressor 15 by means of the conduit 37.

20 While I have shown my invention in but one form, it will be obvious to those skilled in the art that it is not so limited, but is susceptible of various other changes and modifications, without departing from the spirit 25 thereof, and I desire, therefore, that only such limitations shall be placed thereon as are imposed by the prior art or as are specifically set forth in the appended claims.

What I claim is:

30 1. In a refrigerating apparatus in which a working fluid composed of an intimate mixture of a refrigerant and a lubricant is employed, the combination of a condensing chamber, means for maintaining a body of liquid working fluid therein, a compressor disposed within the condensing chamber and above the level of the liquid working fluid, means for passing liquid working fluid over the compressor, whereby the heat of the 35 compressor is utilized to vaporize off the refrigerant contained in the liquid working fluid, means disposed within the condensing chamber for collecting the liquid working fluid which has been subjected to the heat of the 40 compressor, and means for utilizing the collected liquid to lubricate the apparatus.

2. In a refrigerating apparatus in which a working fluid composed of an intimate mixture of a refrigerant and a lubricant is employed, the combination of a condensing chamber, means for maintaining a body of liquid working fluid therein, a motor casing provided within the condensing chamber, said motor casing having a portion thereof 50 disposed above the level of the liquid working fluid, a motor disposed within the motor casing, means for passing liquid working fluid over that portion of the motor casing which is disposed above the level of the liquid working fluid contained in the condensing chamber, whereby the heat of the motor is utilized to vaporize off the refrigerant contained in the liquid working fluid, means disposed within 55 the condensing chamber for connecting the liquid working fluid which has been subjected

to the heat of the motor, and means for utilizing the collected liquid to lubricate the apparatus.

3. In a refrigerating apparatus in which a working fluid composed of an intimate mixture of a refrigerant and a lubricant is employed, the combination of a condensing chamber, means for maintaining a body of liquid working fluid therein, a compressor disposed within the condensing chamber and above the level of the liquid working fluid, a motor casing provided within the condensing chamber, said motor casing having a portion thereof disposed above the level of the liquid working fluid contained in the condensing chamber, a motor disposed within the motor casing, means for passing liquid working fluid over the compressor and over that portion of the motor casing which is disposed above the level of the liquid working fluid contained in the condensing chamber, whereby the heat of the compressor and the motor is utilized to vaporize off refrigerant contained in the liquid working fluid, means for collecting the liquid working fluid which has been subjected to the heat of the compressor and the motor, and means for utilizing the collected liquid to lubricate the apparatus.

4. In a refrigerating apparatus in which a working fluid composed of an intimate mixture of a refrigerant and a lubricant is employed, the combination of a compressor, means for subjecting the liquid working fluid discharged from the compressor to heat for vaporizing off refrigerant from the liquid working fluid, a reservoir disposed below the compressor, and means for conveying the liquid working fluid which has been heated to said reservoir.

5. In a refrigerating apparatus in which a working fluid composed of an intimate mixture of a refrigerant and a lubricant is employed, the combination of a compressor, means for subjecting the liquid working fluid discharged from the compressor to the heat of the compressor to vaporize off refrigerant from the liquid working fluid, a reservoir disposed below the compressor, and means for conveying the liquid working fluid which has been subjected to the heat of the compressor to said reservoir.

6. In a refrigerating apparatus in which a working fluid composed of an intimate mixture of a refrigerant and a lubricant is employed, the combination of a compressor, a motor for driving the compressor, means for subjecting the liquid working fluid discharged from the compressor to the heat of the compressor and the motor for vaporizing off refrigerant from the liquid working fluid, a reservoir disposed adjacent to the motor, and means for conveying the liquid working fluid which has been subjected to the heat of the compressor and the motor to said reservoir.

7. In a refrigerating apparatus in which a liquid working fluid composed of an intimate mixture of a refrigerant and a lubricant is employed, the combination of a compressor, a motor disposed below the compressor, means for subjecting liquid working fluid discharged by the compressor to the heat of the compressor and thence to the heat of the motor, for vaporizing off refrigerant from the liquid working fluid, a reservoir disposed below the compressor and adjacent to the motor, means for conveying the liquid working fluid which has been subjected to the heat of the compressor and the motor to said reservoir, and means for utilizing the liquid working fluid within the reservoir to lubricate the apparatus. 70
8. In a refrigerating apparatus in which a working fluid composed of an intimate mixture of a refrigerant and a lubricant is employed, the combination of a condensing chamber, means for maintaining a substantially constant level of liquid working fluid therein, a compressor disposed within the condensing chamber and above the level of the liquid working fluid, means for substantially separating the refrigerant vapors and liquid working fluid discharged by the compressor and for directing the liquid working fluid upon the hot outer surfaces of the compressor, whereby refrigerant contained in the liquid working fluid is vaporized off, and means for storing a substantial quantity of the liquid working fluid thus treated. 80
9. In a refrigerating apparatus in which a working fluid composed of an intimate mixture of a refrigerant and a lubricant is employed, the combination of a condensing chamber, a motor casing disposed within the condensing chamber, a motor disposed within the motor casing, a compressor superimposed upon the motor casing, means for maintaining, below the upper surface of the motor casing, a substantially constant level of liquid working fluid within the condensing chamber, a baffle for substantially separating the vapor and liquid working fluid discharged by the compressor and for directing the liquid working fluid upon the compressor and a portion of the motor casing, a reservoir for collecting the liquid working fluid thus treated, and means for utilizing said liquid working fluid to lubricate the apparatus. 90
10. In a refrigerating apparatus in which a working fluid composed of an intimate mixture of a refrigerant and a lubricant is employed, the combination of a condensing chamber, a motor casing disposed therein, a motor disposed within the motor casing, a compressor superimposed upon the motor casing, means for passing liquid working fluid over the compressor and thence over the motor casing, whereby the liquid working fluid absorbs heat from the compressor and the motor, a trough for collecting the liquid working fluid, a reservoir disposed below and communicating with said trough, and a conduit for conveying the liquid working fluid from the reservoir to the compressor for sealing and lubricating purposes. 100
11. In a refrigerating apparatus in which a working fluid composed of an intimate mixture of a refrigerant and a lubricant is employed, the combination of a condensing chamber, a motor casing disposed therein, a compressor superimposed upon the motor casing and discharging into the condensing chamber a mixed refrigerant vapor and liquid working fluid, a baffle for substantially separating the refrigerant vapor and the liquid working fluid discharged by the compressor, said baffle being so disposed within the condensing chamber as to cause the liquid working fluid to fall upon the compressor and thence to flow downwardly over the motor casing, a trough surrounding the motor casing for collecting the liquid working fluid which has been subjected to the heat of the compressor and the motor, a baffle for preventing liquid working fluid which has not been subjected to the heat of the compressor and the motor from falling into said trough, a reservoir disposed below and communicating with the trough; and a conduit, subject to the pressure prevailing within the condensing chamber, for conveying the liquid working fluid within the reservoir to the apparatus for sealing and lubricating the same. 110
12. In a refrigerating apparatus in which is employed a lubricant which may take into solution some of the liquid refrigerant, the combination of a compressor, a motor for driving the compressor, means for passing the lubricant over a portion of the compressor and the motor, whereby liquid refrigerant in solution with the lubricant is vaporized off, and means for draining the lubricant thus treated to a reservoir. 120
13. In a refrigerating apparatus in which is employed a lubricant which may take into solution some of the liquid refrigerant, a compressor, a motor for driving the compressor, a casing enclosing the motor and the compressor, means for subjecting the lubricant to heat, whereby the liquid refrigerant in solution with the lubricant is vaporized off, and means for draining the lubricant thus treated to the lower portion of the casing. 130
14. In a refrigerating apparatus in which is employed a lubricant which may take into solution some of the liquid refrigerant, a compressor, a motor for driving the compressor, a casing enclosing the motor and the compressor, means for subjecting the lubricant to the heat of the compressor, for vaporizing off the refrigerant in solution therewith, and means embodied in the lower portion of the casing for collecting the lubricant thus treated. 140

15. In a refrigerating apparatus in which is employed a lubricant which may take into solution some of the liquid refrigerant, a compressor, a motor for driving the compressor, a casing enclosing the motor and the compressor, means for subjecting the lubricant to some of the heat generated by the compressor and the motor, whereby liquid refrigerant contained in solution with the lubricant is vaporized off, means embodied in the lower portion of the casing for collecting the lubricant thus treated, and means associated with the casing for condensing the refrigerant vaporized by the heat of the compressor and the motor.
16. In a refrigerating apparatus, the combination of a closed condensing chamber, a compressor for discharging compressed refrigerant vapor having liquid entrained therein and disposed within said chamber,
17. In a refrigerating apparatus, the combination of a compressor for discharging compressed refrigerant vapor having liquid entrained therein, a fluid-tight casing enclosing the compressor, baffle means provided within the casing above the compressor for separating out the liquid entrained in the compressed refrigerant vapor, means for collecting the separated liquid in the lower portion of the casing, said means comprising a reservoir below the compressor, and means for condensing the refrigerant vapor.

In testimony whereof, I have hereunto subscribed my name this 29th day of May, 1923.

ANDREW A. KUCHER.
